UNITED STATES PATENT OFFICE.

WALTER R. BROWN, OF DECATUR, ILLINOIS.

INVALID BED.

1,407,631.

Specification of Letters Patent. Patented Feb. 21, 1922.

Application filed October 23, 1920. Serial No. 418,995.

To all whom it may concern:

Be it known that I, WALTER R. BROWN, a citizen of the United States, residing at Decatur, in the county of Macon and State 5 of Illinois, have invented new and useful Improvements in Invalid Beds, of which the following is a specification.

This invention relates to invalid beds, and comprehends a construction to permit 10 use of a bed pan without lifting, rolling or otherwise disturbing the patient.

To this end, the springs and mattress of the bed includes sections slidable transversely of the bedstead, to provide an opening 15 in the bed immediately above the pan support which depends from the side rails of the bedstead.

The nature and advantages of the invention will be better understood when the 20 following detailed description is read in connection with the accompanying drawings, the invention residing in the construction, combination and arrangement of parts as claimed.

25 In the drawings forming part of this application, like numerals of reference indicate similar parts in the several views, and wherein:

Fig. 1 is a side elevation of the bed showing the position of the pan support.

Fig. 2 is a longitudinal sectional view therethrough.

Fig. 3 is a perspective view of the bedstead showing the pan support associated 35 therewith.

Fig. 4 is a fragmentary plan view of the bed springs.

Fig. 5 is a similar view of the mattress.

Referring to the drawings in detail, A 40 indicates generally a bedstead of a standard construction, wherein the side rails are indicated at 10. The springs for the bed is indicated generally at B, and made in sections, including two end sections 11 which 45 are spaced by intermediate sections 12 and 13 respectively as clearly illustrated in Figure 4. The mattress is made up of a similar number of sections, including end sections 14, of an area equal to the end sections 11

50 of the springs, the end sections 14 being spaced by intermediate sections 15 and 16 respectively, which are also of an area equal to the area of the spring sections 12 and 13 respectively. The mattress sections 15 and 55 16 are secured to the spring sections 12 and 13 respectively and move forward as two

units, the units moving toward and away from each other transversely of the bedstead for the purpose to be hereinafter described. To facilitate the movement of 60 these section units, each is provided with a flexible handle 17.

Arranged transversely of the bedstead and depending from the side rails 10 thereof, is a pan support of substantially U- 65 shaped formation in cross section. This support may include spaced angle iron bars 20 between which is supported the channel shaped member 21, or the support in its entirety may be formed from one piece of 70 material. As shown, the support extends across the entire width of the bed with the upper edges of the side bars 20 raised flush with the side rails 10 of the bedstead. The sliding units above referred to, of the mat- 75 tress and spring sections are supported upon the side bars 20 of the pan support, these units being equipped with felt or other suitable material 22 to eliminate noise of any kind while the sections are being ad- 80 justed or moved over the pan support.

In use of the bed, the head and trunk of the patient rest upon one of the end sections 14 of the mattress, the legs on the other end section, while the hips will be supported 85 upon the movable units made up of the sliding spring and mattress sections above described. When use of the bed pan is required, either or both of the sliding units of the springs and mattress may be drawn 90 outwardly beyond the side of the bed, thus providing an opening in the mattress as will be readily understood. The bed pan is then arranged upon the sliding channel member 21, by adjusting the latter with respect to the side bars 20, and the pan may 95 be properly positioned for use.

While it is believed that from the foregoing description the nature and advantages of the invention will be readily apparent, I desire to have it understood that I 100 do not limit myself to the details herein shown and described, and that such changes may be resorted to when desired as fall within the scope of what is claimed. 105

What I claim is:

In combination, a bed including sectional springs and mattress, means for securing the intermediate sections of the springs and mattress together for sliding movement 110 across the bed toward and away from each other, a substantially U-shaped pan support-

ing member arranged transversely of the bed, said member being closed at one end and open at the other, brackets secured to the side rails of the bed and projecting toward each other, inwardly directed flanges formed on the pan supporting member and reposing upon and secured to said brackets,

said flanges lying flush with the upper sides of the rail of the bed and constituting a support for said sliding sections or units 10 of the bed springs and mattress.

In testimony whereof I affix my signature.

WALTER R. BROWN.
